UNITED STATES PATENT OFFICE.

VALENTIN HENNEMAN, OF PROVIDENCE, RHODE ISLAND.

TRAIN-CONTROLLING APPARATUS.

1,278,647.

Specification of Letters Patent. Patented Sept. 10, 1918.

Application filed August 14, 1914, Serial No. 856,815.

To all whom it may concern:

Be it known that I, VALENTIN HENNEMAN, a subject of the King of Belgium, residing at Providence, in the county of Providence and State of Rhode Island, have invented certain new and useful Improvements in Train-Controlling Apparatus, of which the following description, in connection with the accompanying drawings, is a specification, like reference characters on the drawings indicating like parts in the several figures.

This invention relates to mechanism for controlling automatically the running of railway trains of all kinds which are provided with air brakes whether they are propelled by steam, by electricity or otherwise. Mechanism of this kind is usually carried by the leading car or locomotive and is adapted to coöperate with tripping means located on the track or road bed which may be set to cause the mechanism to operate and stop the train.

An object of this invention is to provide a mechanism having these general characteristics which is so constructed as to be unaffected by shocks and vibration due to the normal operation of the train.

An important object of the invention is to provide means which will enable the speed of trains to be controlled from the road bed by varying a characteristic of the trip piece by which the train controlling mechanism is operated.

It is a further object of the invention to provide a mechanism such that if any essential part of it is lost or broken the brakes will be applied as an indication of such defect. Another object of the invention is to provide means for warning the engineer and stopping the train or both in case of accidental derangement of the rails or road bed. Other objects of the invention will appear as the description progresses.

An important feature of the invention comprises a pivoted member which contacts with the trip piece to cause the operation of the controlling mechanism and is so balanced upon its pivot that the shocks incident to stopping, starting, and making up trains have substantially no tendency to move the member about its center of gravity, which movement is utilized to cause application of the brakes. The balanced member is preferably formed as a lever pivoted between its ends and having a roll upon one end ar-

ranged to contact with a trip piece on the rail or road bed. Connections are made from the lever to a valve which when caused to open by a movement of the lever releases compressed air which acts through suitable mechanism to effect the application of the train brakes. The suddenness or rate of application of the brakes depends upon the extent of movement of the lever and hence by changing a characteristic of the trip piece, for example its height, the trains may be stopped, slowed down to varying degrees or permitted to pass unchecked.

It is desirable that the degree to which the brakes are set in a given time shall be dependent upon the speed of the train, and, as a further important feature of the invention, means is provided which will set the brakes of a train that is moving rapidly at a greater rate than those of a train that is moving more slowly, the rate of application being proportional to the speed. This result is effected by a member having considerable inertia which is connected to the balanced lever. The said member, when set in motion, has therefore considerable momentum and its momentum, and hence the distance it moves, is dependent upon its velocity which is of course, dependent upon the velocity with which the balanced lever strikes the trip piece; that is, on the speed of the train. The use of this arrangement in connection with a trip piece of a given height adjustment results in the checking of the speed of a train that is running above a predetermined speed while it allows to pass unchecked a train traveling at a slower rate.

In the case of the slow train the roll of the balanced lever strikes the trip piece gently and has time to ride over it without imparting to the momentum member or to the rotating parts any considerable momentum with the result that the connected parts are not moved sufficiently to cause application of the brakes. In the case of a train running a little above the prescribed rate the balanced lever and momentum member will be give movement somewhat in excess of that required to permit the contact member or roll to pass over the trip piece; the brakes will therefore be slowly applied and the engineer or motorman thereby notified of the fact that he is exceeding the speed limit. Furthermore, if the train is running at a very excessive speed the contact of the balanced lever with the trip piece will be so vio-

lent that the momentum imparted to the momentum member will cause the brakes to be quickly set. The controlling mechanism acts therefore as a vigilant guardian to enforce the speed rules of the road, but it does not interfere, so long as those rules are observed.

The invention also comprises means which acts, after the brakes are set, to prevent the 10 engineer from releasing them for a predetermined length of time which, in case the brakes are quickly set, may be sufficient to bring the train to a full stop. If desired the device may be so set that he will even be 15 compelled to wait a given length of time after the train has been brought to a standstill. The invention also includes means for closing the throttle at the same time that the brakes are applied and holding it closed 20 for a predetermined length of time.

A further feature of the invention is embodied in means by which the controlling means may be reset by the engineer from the cab and preferably a signal is shown 25 and a counter or register operated whenever the mechanism is reset. The counter keeps a record of the number of times the mechanism is operated and hence serves as a check 30 on the engineer as to his manner of running his train.

The engineer may, by operating the resetting mechanism while passing a signal set against him, prevent the automatic stop mechanism from operating but each such operation is 35 recorded by the counter and a signal on the train, which is exposed when the resetting lever is held up, shows to any observer under what conditions the train is being operated.

40 These and other features of the invention will appear more fully from the following description, when read in connection with the accompanying drawings, and will be particularly pointed out in the appended 45 claims.

In the drawings:—

Figure 1 is a diagrammatic view of a locomotive with an embodiment of my invention applied thereto.

50 Fig. 2 is an enlarged side view of the portion of the mechanism which is attached to the cowcatcher.

Fig. 3 is an elevation of Fig. 2.

Fig. 4 is a detail view of the trip pieces.

55 Fig. 5 is a plan view of Fig. 4.

Fig. 6 is an end view of Fig. 4.

Fig. 7 and Fig. 8 are respectively a side and end view of the scraper.

Figs. 9, 10, and 11 are details of the valve.

60 Figs. 12 and 13 are respectively a plan and front view of the throttle lever and the means for releasing it.

Fig. 14 shows the cylinder located in the cab by which the throttle is closed and the 65 brakes set.

Fig. 15 is a sectional detail of the vent valve in the cylinder.

Figs. 16 and 17 are side views of modifications of the mechanism shown in Figs. 2 and 3.

Fig. 1 shows a locomotive provided with one embodiment of the invention operatively connected with the throttle and air valve for reducing the speed of a train or bringing it to a standstill. Certain operative parts of the device are mounted on the pilot of the locomotive the cross beam of which is represented at 2. These parts, which are shown on an enlarged scale in Figs. 2 and 3, comprise a bar 4 rigidly secured to the beam 2. To the lower end of the bar 4 is pivoted at 6 a balanced lever 8. To contact with the trip piece the lever 8 carries preferably a roll 10 at one end. At the other end is a weight 12 sufficient to 80 counterbalance the rotating parts which are on the opposite side of the center 6. By arranging equal weight of the rotating parts on each side of the pivot 6 the movements of the locomotive have no tendency to rotate 85 the lever about its pivot, the latter being at the center of gravity of the lever. A bar 14 is pivoted at 16 to the lever 8 at the rear of the center 6. The bar 14 is provided with a cam face 18 which acts on a roll 20 90 on one end of a lever 22 which is pivoted at 24, and is guided near its lower end by an encircling strap 23. Opposite the roll 20 a second roll 26 is provided which serves as an antifriction bearing for the bar 14. The roll 26 is preferably not attached directly 100 to the bar 4 but to a link 28 pivoted at 30 to the bar 4. An adjusting screw 32 passes through a lug on the bar 4 and engages the link 28. The purpose of this adjustment 105 will appear hereinafter. Below the pivot 24 of the lever 22 is a slide valve 34, shown in detail in Figs. 9, 10 and 11, which bears against the lever 22 and is held closed 110 thereby. The valve 34 closes the passage in a pipe 36 leading from the pressure tank 38 on the locomotive (Fig. 1) to a cylinder 40 in the cab. As air pressure is maintained in the tank 38 at about 200 pounds per square inch the valve is held against the lever 22 with considerable force and tends 115 continuously to open. When the parts are in normal position with the wide part of the bar 14 between the rolls 20, 26 the screw 32 is adjusted so as to maintain the valve 120 34 closed. The valve is held open to give the mechanism located in the cab time to act by a rod 42 pivoted at 44 to the lever 8 and having teeth 46 at its upper end. A catch 48 which is held normally in operative position by a spring 49, cooperates with the teeth 46 to hold the lever 8 in the position to which it is moved by the passage of the roll 10 over a trip piece 50 which is 125 mounted by the side of the rail 45 in proper 130

position to coöperate therewith. The trip piece 50 has inclined faces 52, 54 and is mounted on a support 56, Fig. 4 which is pivoted at 58 to swing into and out of position to be engaged by the roll 10. The trip piece 50 is held normally in operative position by a spring 60 against a stop 64 which has a sharp edge to engage the piece 50. This formation insures that any ice or snow 10 which may collect on the parts between the piece 50 and the stop 64 will be knocked off and that any object that may fall between them will be likely to be pushed out of the way when the piece is moved into operative 15 position. The spring 60 is provided with a telescopic housing 66, to prevent anything from coming in contact with the spring and interfering with its action. The piece 50 is moved out of operative position by a rod 20 68 which may be connected with any of the usual semaphore or switch signals or their operating devices or the trip piece may otherwise be held out of operative position so that when the track is clear or the switch 25 closed the trip piece 50 will be swung about its pivot to a position in which it will not engage the roll 10 carried by a passing locomotive. When, however, the track is occupied, a switch open or the track blocked 30 for any other reason, the trip piece 50 will be moved into operative position and in case the rod 68 should break or be disconnected the spring 60 will draw the trip piece into operative position and insure that the 35 train be stopped and the trouble located.

Supposing the trip piece to be in operative position and a train be passing, the roll 10 will engage the inclined face of the piece 50 and the lever 8 will be moved about 40 its center 6 as the roll passes over the trip piece. This movement of the lever causes the bar 14 to move up until the inclined face 18 permits the lever 22 to move under the pressure of the valve 34 and the valve 45 to open. The valve is held open by engagement of the teeth 46 with the catch 48 and air is permitted to pass through the pipe 36 to the cylinder 40. A piston in the cylinder 40 operates through a piston rod 50 70 and suitable connections as 72 to close the throttle 74 and open the air valve 76 to set the air brakes.

As the throttle lever is usually held open by a catch it is necessary to provide means 55 by which the lever may be released by the pull of the cable 72. Mechanism for this purpose is shown in Figs. 12 and 13. The lever 74 is held in various open positions by the engagement of a catch 75 with one of a 60 series of notches in a segment 77. The catch 75 is withdrawn by movement of a finger lever 81 toward the lever 74 either by the hand of the engineer or by movement of a releasing member 83 pivoted at 85 to the 65 lever 74 and having a portion 87 adapted to

engage the lever 81 when a pull is given to the connection 72. A pull on the connection 72 acts first to swing the member 83 about its pivot 85 and cause the portion 87 to engage the finger lever 81 and operate it to 70 release the catch 75; further pull on the connection then acts to close the throttle by movement of the lever 74.

To reset the parts for the next operation and to enable the engineer to again start the 75 train, a lever 80 is provided in the engine cab, Fig. 1, which is connected by a flexible connection 82 with a lever 84 pivoted at 86 and having an arm 88 arranged to engage a coöperating arm 90 on the catch 48. When 80 the lever is operated to pull upon the connection 82 the lever 84 rotates about its pivot 86 and the arm 88 first contacts with the arm 90 to disengage the catch 48 and then contacts with an upward extension 92 85 of the lever 22 and acts thereupon to swing the lever 22 to close the valve 34 and allow the cam bar 14 to drop back into normal position. To return the lever 84 to normal position after the lever 80 is released, a weight 90 94 is provided and on this weight may be conveniently mounted a counter or register which will record the number of actuations of the lever 84 and thereby serve as a check on the engineer and deter him from attempting to run by a stop signal by holding the lever 80 and preventing the automatic operation of the mechanism. The counter may comprise a toothed wheel 96 which is connected with suitable indicating mechanism 100 and is engaged by a spring actuated pawl 98, the wheel 96 being rotated one tooth every time the lever 84 is operated.

A light signal is also connected with the lever 84 which acts to expose a light, preferably colored, when the lever is held up to prevent operation of the stop mechanism thus showing an observer the conditions under which the train is being run. Of course, if desired, a white light may be shown normally and a colored light when the lever is raised and the usual colored signals may be shown in the day time. The signal comprises a box 100 in which is a rotating shield 102 having a stem 104 supported for rotation in bearings 106, 108. From the stem 104 extends an arm 110 which is connected by a bar 112 with the lever 84. The shield 102 has two openings, one 114 to register with the open front of 115 the box 100 Fig. 3 when the lever is in normal position and another containing glass of a different color which will register with the open front when the lever is raised.

It is desirable that the engineer be obliged 120 to wait a certain length of time after his train has been automatically stopped by a set signal before he can again start it. This is effected by the cylinder 40 Figs. 1, 14 and 15, which retains the air pressure and holds 125 130

the throttle closed and brakes set even after the lever 80 has been operated to reset the parts and close the valve 34. The cylinder, however, is provided with a vent 118 which allows the air slowly to escape so that after a given time, depending upon the adjustment of the vent, the throttle may again be opened and the brakes released.

The operation of the device, as above described, takes place when the engineer attempts to run by a set stop signal. It is desirable, however, that mechanism be provided that will act slowly to set the brakes of a train which attempts to pass a signal or stop at a speed greater than a prescribed maximum and which will allow trains to pass without setting their brakes if they are traveling below that maximum speed. It is also desirable that the brakes of a train running by a stop or slow signal at a speed very much above the prescribed maximum be set much more suddenly than the brakes of a train which is traveling at a rate only a little above the maximum. These results are effected by the mechanism already described with the addition of a weight or momentum member 120, Figs. 2 and 3. This weight increased the inertia of the system moved by contact of the roll 10 with the trip piece 50 and hence the momentum of that system when once in motion and that motion will be proportional to the velocity with which the roll strikes the stop piece 50.

When the train is moving at a high rate of speed the roll 10 will strike a harder blow upon the inclined face of the trip piece 50, that is the roll and lever will be lifted to the height of the trip piece in a shorter interval of time and hence a greater velocity will be imparted to the weight 120 thereby increasing its momentum and consequently the movement of the connected parts. This greater movement causes the cam 18 to move farther and permit the valve 34 to open wider and a lower tooth 46 on the rod 42 to be engaged by the latch 48. This, of course, causes a more sudden application of the brakes. If however, the speed of the train has already been reduced below the limit of speed allowed for safety the roll 10 will ride over the incline 50 without being raised far enough to open the valve 34 at all and hence the progress of the train is not interfered with by the automatic controlling device. The device, therefore, simply stands guard over the track, permitting trains running at proper speed to pass unchallenged but reducing their speed if they attempt to pass that point at a speed greater than is considered safe, the speed at which they may pass unchecked depending upon the height adjustment of the trip piece. The trip piece shown in Figs. 4 and 6, later to be described, is well adapted for speed regulation.

In Figs. 16 and 17 are illustrated modified mechanisms in which features of my invention may also be embodied. In these figures the parts which are identical in structure and function with the corresponding parts of Figs. 2 and 3 are given the same reference numerals.

In Fig. 17 only the parts corresponding to the parts 14 and 26 of Fig. 3 are modified. The cam face 18 instead of being formed on the bar 14 is made part of a rotating member 25 which is mounted in a manner similar to the roll 26 in Fig. 3 but which comes in direct contact with the roll 20. The cam 25 is operated by a link 15 connected to the lever 8 at the enlarged end, 12, thereof. Movement of the lever 8 obviously will bring the low part of the cam 25 in contact with the roll 20 and the lever 22 will be permitted to move and the valve 34 to open. The remaining parts of this modification are constructed and operate substantially as do the corresponding parts of Figs. 2 and 3. Further description is therefore unnecessary.

In Fig. 16 a further modification is shown in which the cam face which controls the valve 34 is on a lever 9, similar to the lever 8 of Fig. 3 and acts on a roll 11 on a bar 21 mounted to slide freely on the support 4 and carrying at its upper end an adjusting screw 33 which engages a lever 25, pivoted at 27 and supporting the valve 34. The screw 33 has, of course, the same function as the screw 32, Fig. 3. The resetting mechanism comprises a link 41 pivoted at one end to the lever 25 and at the other end to one end of a lever 37 the other end of which carries a link 35 having a lost motion connection with the arm 88 of the resetting lever 84 which permits the latch 48 to be tripped before force is applied to the link 41 to draw up the lever 25 and close the valve. The rod 42 and the weight 120 being first freed tend to turn the cam 8 back to normal position and the cam tends to force the valve closed thereby assisting the lever 84. The form of the cam 19 is such that no practicable pressure on the valve 34 can force it open.

In order that snow or sleet may not interfere with the operation of the automatic stopping device means shown in Figs. 1, 7, and 10 is provided, which consists of a scraper 130 on the end of a rod 132 passing through a bracket 134 on the cow-catcher. The scraper is held depressed in position to contact with the trip pieces 50 of the system by a spring 136, and to take the draft of the scraper a link 138 is connected just above the scraper and to a lug 140 farther forward on the cowcatcher.

While the trip pieces have been referred to as being connected to switch or stop signals or to semaphore or block signals it is to be understood as within my invention to
